UNITED STATES PATENT OFFICE.

WALLA LEVISTON AND JOHN PERRY, OF KANSAS CITY, MISSOURI.

SPRING-WHEEL.

1,350,370.

Specification of Letters Patent. Patented Aug. 24, 1920.

Application filed November 7, 1918. Serial No. 261,580.

To all whom it may concern:

Be it known that we, WALLA LEVISTON and JOHN PERRY, citizens of the United States, residing at Kansas City, in the county of 5 Jackson and State of Missouri, 2905 East 31st St. and 2830 Tracy avenue, respectively, have invented certain new and useful Improvements in Spring-Wheels; and we do declare the following to be a full, clear, and 10 exact description of the invention, such as will enable others skilled in the art to which it appertains to make and use the same, reference being had to the accompanying drawings, and to the letters and figures of reference marked thereon, which form a part of 15 this specification.

This invention relates to spring wheels and particularly to wheels capable of supporting heavy loads.

20 One of the objects thereof is to provide a wheel which will have the advantages of a pneumatic tired wheel without its disadvantages. Another object is to provide a spring or set of springs around the periphery of the felly which, in service, will have a rolling action so that there will be no local bending strains tending to cause crystallization of the material of which the spring is made.

25 30 Other objects and advantages will be apparent hereinafter as the nature of the invention is better understood, it being apparent the changes in form, proportion and minor details of construction may be resorted to without departing from the spirit of the invention or sacrificing any of its advantages.

In the drawings

Figure I is a transverse sectional view 40 through a wheel constructed in accordance with our invention.

Fig. II is a fragmentary perspective view of a completed wheel and

Fig. III is a detail perspective view of one 45 of the springs.

Referring now to the drawings by numerals of reference:

1 designates a hub which may be of any preferred construction and from which radiate spokes 2, having tenons 3 received within the felly 4 in the usual manner. 5 designates a peripheral band embracing the felly 4 as shown in Figs. I and II. 6 designates the rim which may be provided with 55 the reinforcing band 7 on which may be placed the tire 8 having a rubber or resili-

ent tread 9. The rim and the felly are connected together by springs arranged in pairs and extending in circular series entirely around the periphery of the felly. The specific form of springs is best shown in Fig. 60 III as comprising an outwardly projecting leaf 10 and an inwardly projecting leaf 11 connected by an intermediate transversely disposed loop 12, the end curved portion 65 13 of which is struck on substantially the same radius as the curved portions 14 and 15. By so constructing the loop the leaves 10 and 11 are connected by a loop consisting of a double compound parabolic curved portion 70 so that when the spring is put under tension, that is, when one leaf is moved in the direction of the other, there will be a rolling motion imparted to the body portion of the loop so that there will be no local bending 75 thereof to cause crystallization of the material. This is an important advantage inasmuch as springs heretofore used for similar purposes have had a tendency to quickly become weakened or break on account of 80 the crystallization due to the vibration of the wheel passing over an uneven surface.

By referring to Fig. I, it will be observed that the leaf 11 is slightly off-set with respect to the leaf 10 due to the fact 85 that the felly is of slightly less width than the rim. By referring to Fig. I it will also be observed that the sides of the felly are reinforced by rings 16 and 17; similar rings 18 and 19 reinforcing the sides of the rim 6. 90 Between these reinforcing rings and the clamping rings 20 and 21 are secured the off-set ends 11 of the springs; these being secured by the through bolts 22. The leaves 10 are fastened against the rings 18 and 19 95 on the rim by the clamping rings 23 and 24, through bolts 25 being secured to fasten these in place.

Inasmuch as the springs are arranged in pairs with their loops inwardly disposed, a 100 tendency of the rim to become displaced due to side thrusts, will be strongly opposed because the tension on the sides of the wheel is equal and opposite. Attention is also directed to the fact that inasmuch as the 105 springs are arranged in circular series between the felly and the rim, there will be tension applied to each spring whenever a load is placed on the wheel, thus equalizing the load throughout the springs in an efficient manner.

The top springs will have a tendency to

open while the lower springs close and the side springs will permit relative sidewise movement between the leaves 10 and 11 as has been demonstrated in actual commercial 5 application of the invention.

What we claim and desire to secure by Letters-Patent is:

A spring wheel comprising a hub and spokes, a rim spaced from the felly, springs 10 arranged in circular series about the felly and the rim and having intermediate loops projecting laterally between the felly and the rim, said springs being arranged in pairs in transverse relation, the loops in each

spring being in the form of a double compound curve providing a contracted loop having alining outwardly and inwardly projecting ends lying against the outer edges of the rim and felly, and circular clamping plates extending around the felly and 20 rim on opposite sides, between which and the rim and felly the respective ends of the springs are secured.

In testimony whereof we affix our signatures.

WALLA LEVISTON.
JOHN PERRY.
